UNITED STATES PATENT OFFICE.

GUSTAF DAVID SUNDSTRAND, OF ROCKFORD, ILLINOIS, ASSIGNOR, BY MESNE ASSIGNMENTS, TO SUNDSTRAND ENGINEERING COMPANY, OF ROCKFORD, ILLINOIS, A CORPORATION OF ILLINOIS.

OIL BURNER.

Application filed May 19, 1924. Serial No. 714,212.

This invention has reference to oil-burning apparatus of the type used in heating dwellings, apartment houses, factories, etc., and relates particularly to the construction of the 5 parts located within the furnace.

Ordinarily oil burners having a combustion bowl and a forced air supply thereto introduce the air at a considerable velocity. High velocity in burners is undesirable since 10 it tends to create noise and to carry the air and fuel out of the combustion chamber before completion of combustion.

It is the object of this invention to provide a means and method of mixing fuel with a 15 forced air supply to assure a quiet and efficient combustion.

It is another object of this invention to provide a structure dividing and distributing the supplied air in a manner to avoid high 20 velocities.

Another object is to provide a combustion bowl having a central supply of air thereinto against deflecting baffles.

Another object of the invention is the provision of a series of spaced conical frustums disposed in the path of the entering air as the deflecting baffles. 25

Still another object is the provision of a fuel nozzle arranged to spray fuel against 30 the air leaving the bowl.

In the drawings there is illustrated a structure embodying the invention, Figure 1 representing the mechanism which is located outside the furnace, and

35 Fig. 2 illustrating the parts located within the furnace. Fig. 3 is an enlarged cross-section of one of the baffles along the line 3—3 of Fig. 2.

In the drawings an air blower is provided 40 comprising a casing 5 and a fan 6. The blower is associated with suitable mechanism for controlling the air and fuel supplies, such mechanism forming no part of this invention. A conduit 7 leads from the blower to 45 the burner bowl shown in Fig. 2. In the present instance the bowl 8 is shown as being circular in form and is horizontally disposed. The bowl is supported upon an elbow 9 which is part of and the termination of the 50 conduit 7. Suitable legs 10 support the elbow when required. The top of the elbow 9 has a circular opening, in the present instance slightly enlarged over the normal diameter, thereby forming the shoulder 11 and annular

flange 12. The bowl 8 has a downwardly 55 projecting annular flange 13 fitting within the flange 12 and resting on the shoulder 11. The bowl has its bottom 14 open within the annular flange 13 for admission of the air. Inside the bowl a ring 15 is shown about the 60 bottom opening. The bottom 14 slopes slightly upwardly and terminates in a cylindrical wall 16. In the bottom of the elbow 9 a depression 17 is formed defining a chamber 18. From this chamber extends a pipe 20 65 for draining oil from the burner in case of continued supply when there is no combustion.

In the casing of the elbow 9 there is supported a vertical stem 21 axially aligned with 70 the center of the bowl and the bowl-end of the elbow. For this purpose a supporting socket 22 is cast into the elbow to insure a rigid vertical support of the stem 21. The upper end of the stem has a plurality of 75 baffles thereon arranged to cover completely the air-opening in the bottom of the bowl. The baffles are disposed so as to deflect the air entering vertically to a substantially horizontal path. And furthermore a plurality of baffles is provided and arranged to divide the single stream of entering air into a number of streams or horizontal radial sheets of air. 80

The baffles of the drawing are shown as being four in number as 23, 24, 25 and 26. Each baffle is a frustum of a conical shell and each is supported by the rod 21 lying in the cone axis. The lowermost frustum 23 is the larger, and each frustum in succession has its lower base overhanging the upper end or base of the frustum beneath it and vertically spaced above it. For example the frustum 23 has the upper end 27 disposed below the lower base 28 of the baffle 24, forming the horizontal space 29 therebetween from which may issue a sheet of air. Each of the baffles 23, 24 and 25 is open at its upper and lower ends. A spider 30 (Fig. 3) is formed in each one and is provided with a central member 31 for support by a shoulder or reduced portion 32 of the stem 21. The topmost baffle 26 has a closed upper end 33 to serve as a cap for the series and is supported on the end of the stem 21. 90

In Fig. 2 a nozzle 34 is shown located in line with the stem 21 and spaced above the baffles. Oil or a mixture of oil and air is sprayed from the nozzle in a path generally indicated by numeral 35. The bowl of the drawings is in 100 105

tended for relatively large installations and is about fifteen or eighteen inches in diameter. The nozzle for such a bowl is placed about eight or ten inches above the top of the cone 26.

5 In the operation of the apparatus disclosed in the drawings, the air is emitted radially in four lateral sheets, which merge together and impinge on the side wall 16. At the wall the air naturally becomes deflected upwardly 10 thereby tending to form a cylindrical shell or envelope above the bowl. But one sheet of air and part of a second are emitted in a line above the wall 16. These sheets being weaker in force because of the smaller diameter of the 15 upper baffles, likewise merge into a horizontal current which tends to spread out the cylinder of air from the lower baffles, thereby enlarging it to fill the space above and laterally outside of the bowl. The oil being sprayed 20 into the path of the air is carried by the laterally traveling sheets, whereby it is well distributed throughout the furnace to cause an efficient and complete combustion.

While the above type of bowl and baffles 25 produces a mixture of air and fuel in the manner and of the type described, it is within the scope of this invention, as defined in the appended claims, to provide other structures to accomplish the same purpose according to the 30 principles above set forth.

I claim as my invention:

1. An oil burner having, in combination, an air blower, a burner bowl, an air conduit from

the blower to the bowl, said conduit entering the bowl axially thereof, a plurality of spaced 35 cone-shell frustums disposed in the bowl over the opening of the conduit, said frustums decreasing in size away from said opening, the lower base of one frustum being larger than the upper base of the next lower frustum, the 40 uppermost frustum having an imperforate upper end, supporting means for said frustums, and a fuel nozzle disposed above said frustums.

2. An oil burner having, in combination, a 45 forced air supply, a burner bowl, an air conduit entering said bowl axially thereof and connected to said air supply, a plurality of spaced overlying conical shell frustums covering the opening of said conduit, said frustums 50 decreasing in size away from the opening, a cap for said frustums, and a fuel nozzle disposed above said cap.

3. A fuel burner having, in combination, a 55 bowl, a supporting elbow therefor, a forced air supply, a conduit therefor, said elbow being in the conduit to carry the air, the bowl having an annular bottom with its opening in register with the elbow opening, a stem supported axially of said opening, a plurality of cone 60 frustums carried by said stem, and a fuel nozzle disposed above said frustums.

In testimony whereof, I have hereunto affixed my signature.

GUSTAF DAVID SUNDSTRAND.
